UNITED STATES PATENT OFFICE.

NEWTON WHITESEL AND FREDERICK WHITESEL, OF WATERTOWN, NEBRASKA.

WIRE-STRETCHER.

1,110,473.

Specification of Letters Patent. Patented Sept. 15, 1914.

Application filed May 11, 1914. Serial No. 837,848.

To all whom it may concern:

Be it known that we, NEWTON WHITESEL and FREDERICK WHITESEL, citizens of the United States, residing at Watertown, in the county of Buffalo and State of Nebraska, have invented certain new and useful Improvements in Wire-Stretchers; of which the following is a specification, reference being had to the accompanying drawings.

This invention relates to wire stretchers.

The object of the invention is to provide an article of this character which shall be thoroughly effective in placing a fence wire under tension and retaining it in taut condition until properly stapled to the post, the construction and operation of the parts being such as to insure the highest efficiency and durability in use with the minimum of danger of derangement or breakage of any of the elements.

A further object is to construct the operating lever in such a manner as will permit of the stretcher being turned over without any danger of the wire becoming disconnected from the implement.

A further object is to adapt the appliance for use in connection with posts of different sizes, whereby materially to increase the usefulness of the tool as a whole.

With the above and other objects in view, as will appear as the nature of the invention is better understood, the same consists in the novel construction and arrangement of parts of a wire stretcher as will be hereinafter fully described and claimed.

In the accompanying drawings forming part of this specification, and in which like characters of reference designate corresponding parts: Figure 1 is a top plan view of the stretcher; Fig. 2 is a view in side elevation displaying the stretcher positioned relative to a post; Fig. 3 is a top plan view similar to Fig. 1, but taken from the reverse side of the stretcher; Fig. 4 is an end view of the operating head; Fig. 5 is a top plan view of a portion of the operating lever, showing the manner in which the pulling dog is held out of operative relation by the spring that serves to hold it in contact with the wire when the latter is being stretched; and Fig. 6 is a sectional detail view of a part of the implement.

The post clamp or anchoring member comprises a head 1 from which project two arms, 2 and 3, of the same length and held spaced

apart by a brace 4, and a third arm 5 disposed at right angles to the arms 2 and 3, the inner faces of the three arms being provided with spurs 6 that are designed to sink into the post and thus operate to hold the implement rigid relative thereto and against any possibility of turning or slipping. The arms 2 and 3 are provided intermediate their ends with two rearwardly projecting ears 7 and 8, and secured to the head 1 is a fourth arm 9, which is provided with spurs 10 similar to those on the other arms, the arm 9 being disposed in parallelism with the arm 5, but being considerably shorter than the latter arm. Disposed between the ears 7 and 8 is a grooved sheave 11 having integral therewith a ratchet wheel 12, and projecting through the ears and the sheave and ratchet wheel is a shaft 13 that is carried by and disposed at right angles to a lever 14, the shaft being rigid with the sheave 11, and being held against disconnection from the ear 8 by a cotter pin 15 that extends through a transverse opening in the end of the shaft 13 that projects through the ear 7. The ratchet wheel is designed to be engaged by a pawl 16 that is pivoted to the arm 2, as clearly shown in Fig. 3.

The arm 5 is provided with a longitudinal slot 17, the inner wall of which is furnished with a series of seats 18 that are designed to be engaged by a pin 19 extending through a yoke 20 carried by the shank of a hook 21, the hook being arranged to be engaged by the links of a post clamping chain 22 that is secured to the sheave 11. The provision of the slot 17 and seats 18 is of importance, as by this arrangement the stretcher can be used with posts of different sizes, it being merely necessary to slip the hook along the arm 5 and bring the pin 19 into engagement with the seat nearest the post whereupon the hook will be locked against slipping.

The head 1, to which reference has been made, is provided with a chamber 23 in which is arranged a wire holding dog 24, the latter being provided with the usual serrations to bite into the wire, W, and also to force the wire against the adjacent wall 25 of the head. The outer wall 26 of the chamber is divided to provide a passage way 27 through which the wire may be inserted within the head and against the wall 25, one of the wall members 26 serving to prevent the wire from working out the chamber. The holding dog 24 is rigidly secured to a

shaft 28 that is carried by a lever 29, from which projects a pin 30, this pin being engaged by one end of a coiled spring 31, the other end of which is secured in a pin or 5 stud 32 projecting upward or outward from the arm 2. The connection of the spring with the lever 29 is such that when swung to a position to shift the holding dog from operative to inoperative position, the lever 10 will pass the dead center and thereby cause the spring to operate to hold the dog in an operative position until the lever is again shifted to bring it past the dead center in an opposite direction, whereupon the spring 15 31 will exercise its function and cause the dog to grip the wall 25 of the chamber 23.

Swiveled upon the shaft 13 between the ear 7 and the ratchet wheel 12 is the inner end 33 of the operating lever 34. At a point 20 adjacent to the inner terminal of the lever the latter is provided with a head 35 formed with a chamber 36 in which is arranged a pulling dog 37, the latter being rigid with a shaft 38 that carries at one end a lever 39, 25 and projecting outward from this lever is a pin or stud 40 with which connects one end of a coiled spring 41, the other end of which is connected with a stud 42 carried by the inner end of the lever. This spring 30 operates in the same manner as the spring 31 to cause the lever to hold the dog 37 into and out of operative relation relative to one wall 43 of the head 35, the wall 44 being divided to provide a passage way 45 corresponding 35 to the passage way 27 in the head 1, and designed to permit the insertion of the wire within the head, the wall operating to prevent the wire from working out of the head should the position of the implement be reversed for any reason. 40

In the use of the implement, the arms 2, 3, 5 and 9 are brought into engagement with the post, and one of the links of the chain 22 is passed over the hook 21, after which the 45 lever 14 is operated to tighten the chain and thus cause the spurs 6 and 10 of the arms to sink into the post and thus anchor the implement in position. The wire is then passed through the passage way 27, the dog 24 being 50 in unlocked position, and through the passage way 45 in the head 35, and the dog 37 brought into engagement therewith, whereupon the lever 34 is operated to place the wire under the desired tension, and the locking dog is then brought into play and will 55 securely grip the wire and hold it until the operator staples it to the post. This same operation is repeated until all the wires are secured.

60 From the foregoing description it will be

seen that although the improvements of this invention are simple in character, they will be thoroughly efficient for the purposes designed, and will coact in the production of a durable and entirely practical form of 65 wire stretcher.

We claim:

1. In a wire stretcher, a head including a pair of post engaging arms disposed at right angles to each other, having their inner faces provided with spurs, and one of the arms being furnished with a longitudinal slot having one of its walls formed with seats, a hook carried by the latter arm and having a pin to engage the seats, a grooved 70 sheave carried by the other arm, a lever for actuating the sheave, a chain secured to the periphery of the sheave and having its links arranged to engage with the hook, and wire retaining and wire stretching means 75 carried by the head.

2. In a wire stretcher, a head provided with a pair of post engaging arms, a horizontally disposed hook carried by one of the arms, a holding dog pivoted within the head, 80 one of the walls of the head being provided with an entrance throat, a spring drawn lever pivotally connected with the dog, a grooved sheave carried by one of the arms and embodying pawl and ratchet mechanism, a chain having one end secured to the sheave and its other end arranged to be brought into engagement with the hook, and wire retaining and wire stretching means 85 carried by the head.

3. In a wire stretcher, a head having one of its walls provided with an entrance throat, a spring drawn holding dog pivotally mounted in the head, a plurality of arms carried by the head, each of which is provided on its inner face with spurs, and one of the arms being furnished with a longitudinal slot formed with a seat, a hook having a pin projecting through the slot and arranged to engage with the seat, a grooved sheave 100 carried by the other arms and embodying pawl and ratchet mechanism, a chain carried by the sheave and arranged to have its links engaged with the hook, a lever provided with a shaft to which the sheave is 105 rigidly secured, and wire stretching means pivoted upon the sheave carrying shaft.

In testimony whereof we hereunto affix our signatures in the presence of two witnesses.
